UNITED STATES PATENT OFFICE.

LAURENCE ROBERTSON, OF TOLEDO, OHIO.

PUNCH-PRESS FEEDER.

Application filed February 23, 1928. Serial No. 256,259.

This invention relates to a punch press feeder, the use of which makes it possible to operate a punch press continuously and rapidly, and with comparative safety. The invention includes mechanism which is driven from the tool actuating shaft to reciprocate the table which supports the sheet of material to be punched or pressed. The table with the sheet thereon is carried beneath the tool in time to be engaged by the latter upon its downward stroke, and is then withdrawn to a convenient position to receive the next sheet, so that the same operation may be repeated upon the next downward stroke of the tool.

The specific construction of the invention, in its present embodiment, together with its mode of operation and the advantages resulting therefrom, will be more particularly described in connection with the accompanying drawings, in which—

Figure 1 is a side elevation of a punch press with the invention applied thereto.

Fig. 2 is a horizontal section taken substantially on the line 2—2 of Fig. 1.

Fig. 3 is a section taken substantially on the line 3—3 of Fig. 2.

Fig. 4 is a detail view taken approximately on the line 4—4 of Fig. 3.

Fig. 5 is a detail sectional view of the feed barrel and traveler, taken on the line 5—5 of Fig. 2.

The invention is illustrated as applied to a punch press which is mounted in a suitable frame 1 having a head 2 for guiding a vertically reciprocating plunger 3. This plunger is actuated from a crank shaft 4 through the medium of a pitman 5. A fly-wheel 6 is secured to the crank shaft 4 and the latter may be continuously driven by a belt 7 connected with the flywheel, or by any other suitable means.

The plunger 3 carries a head 8 to which a tool 9 may be secured to cooperate with a corresponding die 10, which is mounted on a base 11.

The feeder, which constitutes the subject matter of the invention, comprises a rotatable feed barrel 12 which is supported at one end in bearings 13 mounted at one end of the frame 1. This end of the barrel 12 has a reduced extension 14 to which a crank 15 is secured. This crank is connected by a pitman 16 to a crank 17 secured to the crank shaft 4. The effective length of the crank 17 is somewhat less than that of the crank 15,

so that as the crank 17 revolves with the crank shaft 4 the crank 15 and the feed barrel 12 are rocked back and forth through an arc of somewhat less than 180°.

A traveler 18 is mounted on the barrel 12 and is provided with inwardly projecting lugs 19 which are adapted to ride in worm grooves 20 formed in the surface of the barrel 12. These lugs may be provided with rollers, if desired, to lessen the friction. The traveler 18 is formed with rearwardly projecting arms 21 which are slidably mounted on rods 22, the latter being supported in end brackets 23 mounted at the ends of the frame 1. Thus the traveler 18, supported by the rods 22, serves to support the inner end of the barrel 12 and is reciprocated longitudinally of the barrel as the latter is rocked.

A table base 24 is also carried by the traveler 18 and supports a table 25 through the medium of legs 26. Each of these legs is formed at its upper end with a T-head 27 which is adjustably mounted in a channel 28 formed in the table so that the latter may be adjusted forwardly or rearwardly. The heads 27 are secured in the desired position by set screws 29. The legs 26 are slidably mounted in bores 30 formed in the base 24 and the table 25 is normally held in its uppermost position by coil springs 31, which are mounted in seats 32 and bear against the heads 27.

The table 25 is adapted to carry a sheet of metal 33, to be punched or stamped. The table is formed at its front edge with a flange 34 against which the edge of the sheet 33 is pressed and series of holes 35 may be formed at one side of the table to receive pegs, against which another edge of the sheet 33 may rest. The table is formed with a slot or opening 36 wide enough to uncover the die 10 as the table advances to its innermost position. As the table approaches this position the tool 9 is descending. The head 8 is formed with rearwardly and downwardly projecting arms 37 which engage the table 25 behind the sheet 33 and, just before the tool engages the sheet, the arms 37 engage the table and force the same downwardly against the pressure of the springs 31, leaving the sheet upon the die 10 and clear of the table. The ends of the arms 37 may carry anti-friction balls 38 to facilitate the completion of the inward movement of the table after it is depressed. The inner ends 39 of the grooves 20 are extended substantially at right angles to the axis of

the barrel 12 so that there is a pause in the movement of the table during the final part of the punching or pressing operation. As soon as the tool 9 is withdrawn from the work the 5 table 25 is raised by the springs 31, the sheet 33 is lifted from the die 10, and the table 25 is retracted by the reverse movement of the barrel 12 as the cranks 17 and 15 swing upwardly. A clearing blade 40 may also be provided for clearing the work from the table 10 during the return travel of the latter. This clearing blade, as shown in Fig. 2, may be supported by an arm 41 which may be secured to any suitable part of the frame 1. The blade 15 40 is supported in a position where it will barely clear the blank 33 during the advance of the latter. In most pressing operations, as in shaping tin can covers for instance, the resulting article will stand up from the table 20 25 as the latter is retracted and will be swept therefrom automatically. The blade 40 is inclined at such an angle that the work will be thrown forwardly as it is swept from the table.

25 While I have shown and described in considerable detail one form in which the invention may be embodied, it is to be understood that this is merely for the purpose of illustrating the principle of the invention, and 30 that the form, size and relative arrangement of the various parts thereof may be considerably modified to adapt them to the specific purpose for which the machine is to be used or to accommodate them to various types of 35 punch presses, without any material departure from the scope of the invention as claimed.

What I claim is:

40 1. In a punch press, the combination with a reciprocable plunger adapted to carry a tool, a stationary base for supporting a die, and a continuously rotatable crank shaft for actuating the plunger, of a table reciprocable above said base, and means operated by said 45 crank shaft to advance the table beneath the plunger as the latter descends and to retract said table as the plunger is raised, said table being initially in a work receiving position at one side of the die, leaving the latter uncovered, the central portion of the table being 50 cut away so as to leave the die again uncovered at the conclusion of its advance movement.

55 2. In a punch press, the combination with a reciprocable plunger to which a tool may be secured, a stationary base for supporting a die, and a continuously rotatable crank shaft for actuating the plunger, of a table reciprocable above said base, a rotatably 60 mounted member having a worm driving connection with the table, and mechanism connecting said crank shaft to the rotatably mounted member to drive said member in one direction to advance the table beneath the plunger as the latter descends and to drive

said member in the opposite direction to retract said table as the plunger is raised, said table being initially in a work receiving position at one side of the die, leaving the latter uncovered, the central portion of the table 70 being cut away so as to leave the die again uncovered at the conclusion of its advance movement.

3. In a punch press, the combination with a main frame, a plunger reciprocably mounted in said frame and adapted to carry a tool, a stationary base on said frame for supporting a die, and a continuously rotatable crank shaft for actuating the plunger, of a traveler 75 slidably supported for horizontal movement, a rockable member journaled at one end in the frame, the other end of said member being supported by said traveler and having a worm connection therewith, whereby to reciprocate said traveler as said member is rocked, a 80 table supported by said traveler in position to be moved across the path of the plunger, and means connected with said crank shaft for rocking said member.

4. In a punch press, the combination with a main frame, a plunger mounted for vertical reciprocation therein and adapted to carry a tool, a stationary base for supporting a die, and a continuously rotatable crank shaft for actuating the plunger, of a table for supporting a sheet of metal to be worked upon, the initial position of the table being at one side of the die, leaving the latter uncovered and means operated in synchronism with the crank shaft for advancing the table beneath 90 the plunger before the latter completes its descent and for retracting said table after the plunger begins its upward movement, a portion of the table being cut away so as to leave the die uncovered when the table is at the 95 limit of its advance position.

5. In a punch press, the combination with a reciprocable plunger for carrying a tool, means for securing a die beneath said plunger, and a continuously rotatable crank shaft 100 for actuating the plunger, of a table, a base upon which the table is resiliently supported, said table base being reciprocable horizontally, means operated by said crank shaft to advance the table beneath the plunger as the 105 latter descends and to retract said table as the plunger is raised, said table having a portion cut away so as to leave the die uncovered when the table is advanced, and means carried by the plunger for depressing the table 110 immediately before the sheet is engaged by the tool.

6. In a punch press, the combination with a vertically reciprocable plunger adapted to carry a tool, means for securing a die beneath 115 the plunger, and a continuously rotatable crank shaft for actuating the plunger, of a table for supporting a sheet of metal to be worked upon, a base on which the table is resiliently supported, said table base being 120 125 130

reciprocable horizontally beneath the plunger, a rotatably mounted member having a worm driving connection with the table base, mechanism connecting said crank shaft to 5 the rotatably mounted member to drive said member in one direction to advance the table beneath the plunger as the latter descends and to drive said member in the opposite direction to retract said table as the plunger 10 is raised, said table having an opening which leaves the die uncovered as the table is advanced, and means carried by the plunger for depressing the table immediately before the sheet is engaged by the tool.

15 7. In a punch press, the combination with a main frame, a plunger mounted for vertical reciprocation in said frame and adapted to carry a tool, means for supporting a die beneath said plunger, and a continuously rotatable crank shaft for actuating the plunger, of a table adapted to support a sheet of metal to be worked upon, a base upon which the table is resiliently supported, a traveler to which said table base is secured, said traveler being 20 slidably supported for horizontal movement, a rockable member journaled at one end in the frame, said rockable member being partially supported by the traveler and having a worm connection therewith whereby to reciprocate 25

the traveler and table as said member is 30 rocked, means connected with the crank shaft for rocking said member, said table having a portion cut away so as to leave the die uncovered when the table is advanced, and means carried by the plunger for depressing 35 the table immediately before the sheet is engaged by the tool.

8. In a punch press, the combination with a vertically reciprocable plunger for carrying a tool, means for supporting a die beneath the tool, and a continuously rotatable crank shaft for actuating the plunger, of a table for supporting a sheet of metal to be worked upon, a base upon which the table is resiliently supported, means operated in synchronism with the crank shaft for advancing the table with its base beneath the plunger before the latter completes its descent and for retracting said table after the plunger begins its upward movement, said table having a portion cut away so as to leave the die uncovered when the table is in advanced position, and means carried by the plunger for depressing the table immediately before the sheet is engaged by the tool. 50 55

In testimony whereof, I have hereunto signed my name to this specification.

LAURENCE ROBERTSON.

CERTIFICATE OF CORRECTION.

Patent No. 1,719,195.

Granted July 2, 1929, to

LAURENCE ROBERTSON.

It is hereby certified that error appears in the printed specification of the above numbered patent requiring correction as follows: Page 2, line 102, claim 4, after the word "table" insert the words "to its initial position"; and that the said Letters Patent should be read with this correction therein that the same may conform to the record of the case in the Patent Office.

Signed and sealed this 30th day of July, A. D. 1929.
